UNITED STATES PATENT OFFICE.

FRANK A. LUNDQUIST, OF CHICAGO, ILLINOIS, ASSIGNOR, BY MESNE ASSIGNMENTS,
TO HENRY S. CONRAD, TRUSTEE.

RELAY.

Application filed July 13, 1918, Serial No. 244,731. Renewed May 19, 1923.

To all whom it may concern:

Be it known that I, FRANK A. LUNDQUIST, a citizen of the United States of America, and a resident of Chicago, county of Cook, and State of Illinois, have invented certain new and useful Improvements in Relays, of which the following is a specification.

My invention relates to relays to be used 10 in automatic telephone exchanges, and has for its object improvements in such devices.

In automatic telephone exchanges each subscriber has an individual switch at the central office and two wires extending from 15 his sub-station to his switch. At his switch and bridged between the wires from the sub-station to the switch, are two relays known as "line relays." One of these relays is a fast relay which responds to impulses at 20 the rate of seventy or more per second, while the other is a slow relay which will not respond to impulses as rapid as about forty per second but will respond to impulses considerably slower. These relays 25 are high wound and expensive, and there is a pair of them associated with each switch in the exchange. The object here is to make one relay which will perform all of the 30 functions of both fast and slow relays.

In the accompanying drawings—

Fig. 1 is an elevation of the relay together with such circuits as are necessary to an 35 understanding of the operation;

Fig. 2 is a plan;

Fig. 3 is an enlarged central section 40 through the valve casing; and

Fig. 4 is a section on line 4—4 of Fig. 3.

At 11 on pole piece 12 of coil 13 is pivoted 45 an armature 14. The armature 14 is comparatively heavy and has an arm 15 with insulation 16 on its end. Adjacent to this insulation are contact springs 17 and 18 which are closed when the coil 13 attracts its armature 14.

Supported at a convenient point is an air 50 valve casing 19 which is provided with an inlet pipe 20, an outlet pipe 21, and vent openings 22. Inside of the casing 19 are valves 23 and 24 which have pins 25 and 26 which contact with each other in the reduced channel 27 which connects the valve 55 chambers with the outlet 21.

Air pressure in pipe 20 normally holds the valves in the position shown in Fig. 3. The 55 valve 23 has a pin 28 which extends through

the end of the casing and engages the armature 14 to hold it in its retracted position. A spring 29 acts to pull the armature 14 toward its attracted position and against the push of the pin 28. The tension of the 60 spring 29 is such that its pull on the armature is less than the push of the pin 28, and consequently the armature is normally held in its retracted position. But when a current flows through the coil 13, the magnetic pull 65 on the armature 14, plus the pull of the spring 29, is enough to overcome the air pressure back of valve 24, with the result that the valves are shifted to connect pipe 20 with pipe 21, and cut off the connection to 70 the exhaust vents 22. The compressed air flowing to pipe 21 is conveyed to other apparatus where it performs functions not directly connected with the present invention.

Pivoted to the other end of the pole piece 75 12 is another armature 30, which has insulation 31 on its tail piece bearing against a spring 32. The spring 32 normally holds the armature 30 in its retracted position, but when a current flows through the coil 13 the 80 armature 30 is attracted and moves spring 32 away from and out of electrical connection with spring 33.

Associated with the relay is a battery X and a resistance R. The lines A and B are 85 the wires which extend from the subscriber's local station to the central office. When the subscriber operates his calling device to make electrical connections between wires A and B, a current flows from battery X 90 through the coil 13 and over wires A and B, and then through resistance R back to the battery X.

The result of this current through the coil is that armatures 14 and 30 are attracted. If 95 the connection between A and B is broken and remade rapidly, as is the case in the ordinary calling device for automatic telephone exchanges, then the armature 30 will respond as does the armature of a fast relay, but the armature 14 will act as the armature of a slow relay and not respond. In other words, this relay is a fast relay as far as armature 30 is concerned, and a slow relay 100 as far as armature 14 is concerned.

The reason why the armature 14 is slow 105 to respond is due to the fact that the air pressure push on pin 28 is but slightly more than the attraction of spring 29, and the weight to be moved is comparatively heavy. 110

- In the brief interval during which the circuit is broken through coil 13, this force cannot move the armature 14 sufficiently to open the connections between springs 17 and 18. As far as observation goes, the armature 14 appears to stand absolutely stationary while armature 30 responds fully to the ordinary impulses sent in operating the calling device of an automatic exchange.
- 10 From springs 17 and 18, and 32 and 33, I have shown circuits in dotted lines to other apparatus which may be considered as an arbitrary representation of the next switch in the series through which a call goes. In 15 its operation the relay closes and holds the circuit through the springs 17 and 18, and at the same time sends a series of impulses over the circuit through springs 32 and 33.
- What I claim is:
- 20 1. The combination with a coil, and two armatures therefor, of an air valve operated by one of said armatures, and means involving the action of the air valve by which the armature associated therewith will remain 25 attracted during electrical impulses which will cause the other armature to vibrate.
2. The combination with a magnetic coil and an armature therefor, of an air pressure device acting to move the armature to its 30 retracted position, and a spring acting to move it to its attracted position, the force of the air pressure device being greater than that of the spring but less than that of the spring plus the magnetic pull of the coil.
- 35 3. In combination, a pipe for conveying compressed air, a check valve normally interrupting the flow of air thru the pipe, and a power device arranged to operate by quick successive movements each one of which is 40 of a valve opening character and said device being also arranged to have such series of movements interrupted at any point, said valve being closed by the pressure of the air in the pipe and said valve being loaded 45 so that its closing movement will be too sluggish to permit a closing of the valve in the intervals between the quick movements of the power device.
4. The combination with an air pipe, and 50 an electro-magnet having an armature, of means by which upon rapid impulses flowing thru said magnet air will continue to flow thru said pipe, and a pause in such impulses will cause a stoppage of air flow in said 55 pipe.
5. In a relay, a magnetic coil, two armatures therefor, an air valve and a pair of springs operated by said armatures, means for rapidly operating one of said armatures to cause the operation of said springs, and means cooperating with said air valve to hold the other of said armatures in operated position during the rapid operation of said first mentioned armature whereby said air valve is maintained in operated position. 60
6. In a relay, a magnetic coil, a fast and a slow armature therefor, an air valve operated by said slow armature, a pair of springs operated by said fast armature, means for vibrating said fast armature and additional means cooperating with said air valve to hold said slow armature in operated position during the vibrations of said fast armature. 70
7. In a relay, a magnetic coil having two 75 armatures, a pair of contact springs operated by one of said armatures, an air valve operated by the other of said armatures, means for sending electrical impulses through said coil, said first armature vibrating in response to said impulses to operate said contact springs in accordance with said impulses, and means cooperating with said air valve to cause said other armature to be held in operated position while said impulses 80 are sent through said coil.
8. The combination of a coil having an armature and a spring for making the operation of the armature fast in one direction, with an air valve in which the air pressure 85 cooperates with the spring to make the armature slow acting in the other direction.
9. A magnet having an armature, a spring tending to hold the armature in attracted position, an air valve a pressure of which 90 normally overcomes the tension of said spring to hold said armature in retracted position, means for energizing said magnet, the magnetism in said magnet overcoming the pressure of said air valve and assisting 95 said spring to move the armature to attracted position.
10. The combination with a coil having an armature, of means including a spring and an air valve whereby air pressure acting 100 on said valve controls the position of the armature, and said spring and magnetism acting on said armature controls the position of said valve.
